LINGERIE SUPPORT

Jennie B. Kosht, Glendale, Calif.

Application January 10, 1933. Serial No. 650,975

3 Claims. (Cl. 24—73)

The primary object of my invention is the provision of a device for the support and retention on the shoulders of a person of the lingerie strap encircling the shoulder and by which means, the garment is held to the body of the wearer.

One object of my invention is the provision of a device of said character that will efficiently serve the purpose intended, and, at the same time possess practically every wanted and/or desired characteristic for an object of its kind, to-wit: Daintiness, lightness, easily attachable and detachable, rust-proof, absolutely sanitary and thoroughly practical.

Another object of my invention is the provision of an invisible device that may readily be manufactured in various sizes and worn regardless of the nature of the outer clothing, formal or informal, house, street or evening wear.

A further object of my invention is the provision of a device that will readily permit a plurality of lingerie shoulder straps to be simultaneously supported in position thereby.

A still further object of my invention is the provision of a device that will retain and support the lingerie shoulder strap flat and in an unruffled condition, and that will not fray the edges thereof, both of which unsatisfactory conditions are common to devices of this character purchasable in the market today.

I attain these objects by the device illustrated in the accompanying drawing, in which:

Figure 1 discloses my invention in position on the body of the wearer, dotted lines indicating the invention through the dress of the wearer to which it is secured, the shoulder strap of an under garment being supported thereby.

Figure 2 is a somewhat similar view to Fig. 1, having, however, all but a small portion of the dress removed, the figure indicating my invention secured to the dress and supporting the lingerie shoulder strap.

Figure 3 is a fragmentary view showing my invention inserted in and secured to the outer garment of the wearer with the shoulder strap in engagement thereto, freely longitudinally movable therein, but secured against side movement and displacement from the shoulder of the wearer, and

Figure 4 indicates a modified form of my invention showing a plurality of outer garment engaging members.

Similar numerals indicate like parts throughout the several views, the numeral 1 thus indicates my lingerie support proper, 2 comprises a

bail or recess formed in one of its limb members 5 for engagement of the outer garment of the wearer, one or more of such recess portions adequately functioning to secure the support, said recess having outwardly extending side members 60 3 to permit the lingerie support to set even and the garment to which it is attached smooth, the free end 4 of said recessed limb having a looped eye 6, the other end of said limb being turned upon itself to provide an inverted U-shaped 65 member 7 terminating into a limb 8 parallel to the limb 5 and having a tapered point 9 for contacting and securing the lingerie support to the dress or other garment 10 of the wearer, the dress seam 11 usually providing a suitable attaching surface for the lingerie support, the shoulder strap 12 of the lingerie 13 being securely held against side movement by the limb 8, the tapered point 9 whereof is held in secured 70 engagement in the looped eye 6 of the limb 5, thus holding the lingerie 13 in firm position on the body of the wearer.

In the modified form of lingerie support disclosed in Fig. 4, the bail or recess members 14 and 15 are formed integral with the limb 16, said recessed members having outwardly extending members 18 functioning similarly to the members 3 aforesaid, the end 17 of said limb 16 being turned upon itself to provide an inverted 80 U-shaped member 22, the other end 20 thereof terminating into a looped eye 21 for interlocking engagement of the taper pointed free end 24 of the limb 23 parallel with the aforementioned limb 16, the modification in all respects, save 85 said plurality of recess members, which may even be of a greater number than two, being identically with my invention in its preferred embodiment as hereinbefore set forth.

As a practical article of manufacture, my device is readily produced at no great cost. 90 95 simple, efficient, fool proof and durable, it serves its purpose quite well.

I am aware that slight modifications may from time to time be made in the details of construction illustrated without departing, however, from the scope of the present disclosure, and as defined in the claims which are appended hereto. Hence, I do not limit my present invention to the exact description of construction herein disclosed, but what I do claim is:

1. In a lingerie support, an article of manufacture consisting wholly of an integral piece of spring wire bent upon itself to form a U-shaped member having two outwardly extending limbs, 110 one of said limbs tapering to a point, the other

having a centrally disposed relatively deep recess adapted to receive a portion of the garment to which said support is attached, said recessed limb having an outwardly extending straight 5 end turned upon itself so as to form a loop parallel to said tapered point limb for the engagement thereof, and cooperating therewith to firmly retain the lingerie support in position for supporting the lingerie shoulder strap as de-
10 scribed.

2. In a lingerie support, an article of manufacture consisting wholly of an integral piece of spring wire comprising an inverted U-shaped member to provide a plurality of independent 15 limbs, one of said limbs tapering to a point at its free end, the other of said limbs merging at its free end in an interlocking looped eye formation, said last mentioned limb having a centrally disposed formed recess portion ex-
20 tending outwardly of said limb and whereby

said lingerie support is secured to the garment of the wearer as described.

3. In a lingerie support, an article of manufacture consisting wholly of an integral piece of 80 spring wire relatively formed to provide an inverted U-shaped member comprising a plurality of limbs having free ends, one of said ends tapering to a point, the other turned upon itself to form a looped eye adaptable to engage said pointed end, said looped eye ended limb extending 85 partially straight from said U-shaped portion of said member and parallel to said pointed limb and having a centrally disposed outstanding recess adaptable to the engagement of the garment of the wearer, said recessed portion of 90 said looped eye limb and said pointed limb co-operating to effect concurrent engagement of support to the wearer and securing of the lingerie shoulder strap to the support for the express purpose described.
